UNITED STATES PATENT OFFICE.

JAMES I. POLLAK, OF CHICAGO, ILLINOIS, ASSIGNOR TO U. S. TOOL MANUFACTURING COMPANY, OF CHICAGO, ILLINOIS, A CORPORATION OF ILLINOIS.

SHADE HOLDER.

Application filed February 10, 1923. Serial No. 618,338.

To all whom it may concern:

Be it known that I, JAMES I. POLLAK, a citizen of the United States, residing at Chicago, in the county of Cook and State 5 of Illinois, have invented certain new and useful Improvements in Shade Holders; and I do hereby declare the following to be a full, clear, and exact description of the invention, such as will enable others skilled 10 in the art to which it appertains to make and use the same.

This invention relates to improvements in shade holders, especially for electric light sockets or the like, and has for its particular 15 object the provision of a shade holder which can be readily applied to the common electric socket now on the market, and which, when applied, will securely hold in desired position the shade with which the 20 light is equipped.

One of the important objects of this invention is the provision of a shade holder for electric light sockets or the like, which can be readily detached therefrom so as to 25 allow of the removal of the shade from the light or socket with a minimum expenditure of time and trouble, and which is so constructed that the shade can be readily and conveniently replaced when desired.

30 A further important object of this invention is the provision of a shade holder for electric lights or the like which is made in practically one piece, and which comprises an integral spring hinge element whereby 35 the efficient operation of the same is insured at all times.

Another and further important object of 40 this invention is the provision of a shade holder for electric lights or the like which shall be simple of construction, economical to manufacture, and composed of a minimum of parts so that it will not be liable to breakage, and can be easily operated.

45 Other and further important objects of the invention will be apparent from the disclosures in the accompanying drawings and following specification.

The invention, in a preferred form, is 50 illustrated in the drawings and hereinafter more fully described.

In the drawings:

Figure 1 is a bottom plan view of the improved shade holder of this invention.

Figure 2 is a side elevation of the same.

Figure 3 is a front elevation of the device, showing the latching means. 55

As shown in the drawings:

The reference numeral 10 indicates a circular plate forming the body of the shade holder, and provided with a downwardly 60 extending annular flange 12. Holes 14 are provided in the plate 10 for purposes of ventilation, or for the more ready escape of heated air from around the main holder. The central portion of the plate 10 is cut 65 away to provide a circular opening for the reception of the light socket, and the edges of this opening are bent upwardly, thereby forming an upwardly extending annular flange or collar 16, which fits closely to the 70 light socket when the device is in closed position.

As illustrated in the drawings, the circular plate 10 is provided with a diametrically extending cut or slit, as shown at 18, which 75 practically divides the same into two equal parts. The slit 18 extends upwardly through the collar 16, as best shown in Figure 3, and divides the same into halves to correspond with the halves of the plate 10. 80 The cut 18 extends through the forward portion of the downwardly extending flange or skirt portion 12, as shown at 20 in Figure 3, but the skirt or flange 12 is continuous at a point diametrically opposite the 85 cut 20, as shown at 22 in Figure 1, thereby providing a hinge to allow of a slight opening of the shade holder. As the metal of which the device is composed is preferably 90 resilient, a spring-like hinge is thereby formed, which is integral with the material of the holder itself.

As best shown in Figure 1 of the drawings, the slit or cut 18 is curved away adjacent both sides of the spring hinge portion 22 of the flange 12, as illustrated at 95 24, in order to provide for a better opening of the plate 10 at this point, and also to insure a good spring action of the connecting element at 22.

A spring action locking means is provided on the front portion of the shade holder adjacent the slit 20 in the flange 12, and comprises mainly a plate 26 of suitable metal or the like attached securely to the flange or skirt 12 by means of a bolt or rivet 28. The plate 26 is provided with a projecting tongue 30 in the form of a 100 105

spring-leaf element, as shown in Figure 3, which tongue 30 is so made as to pass underneath a struck-up portion of the skirt member 12, as indicated at 32. A slight protuberance 34 or the like is provided on the tongue or latch member 30 so as to comprise a latching means whereby the shade holder proper may be locked into normal shade retaining position and automatically 10 maintained in such position by means of the co-operation of the protuberance 34 with the forward edge of the struck-up latching means 32. The bent over end 31 of the tongue 30 further provides a retaining 15 means whereby any accidental excessive pulling apart of the two halves of the plate 10 will be prevented. All undue strains on the spring hinge member 22 are therefore avoided.

20 It will be evident that merely depressing the latch member 30 by means of the finger will suffice to make the protuberance 34 pass under the struck-up portion 32 and release the spring means.

25 The downwardly extending annular flange or skirt 12 is provided with slots 38, and in these slots are inwardly struck integral retaining strips 40, which serve to co-operate with the circular lip of the shade 30 holder, and retain the same in position when the device is in locked relation with the lamp socket.

From the drawing, especially Figure 1, it will be noted that the strips 40 are 35 formed with a projecting bend 42 at each end, which preferably extends slightly beyond the circumference of the skirt 12, thereby providing a greater resiliency in the strips, and permitting of slight adjustments when same become necessary on account of the use of the device with different shade holders, which may vary slightly in size.

40 It will be seen that herein is provided a shade holder which can be very economically manufactured, in that it is comprised of practically one piece, which can be made in a single stamping operation, which operation will also serve to punch out the 50 necessary ventilating holes 14, and also to cut the slits 18 and 20. The inwardly struck shade supporting members 40 can then be formed in another operation, which operation may also comprise the punching 55 up of the latch locking member 32. The latch means 26, 30, 31 can then be applied by means of the rivet 28, and the device is completed.

60 It will be further evident that the simplicity of this device will recommend it for universal use, as the shade holders now on the market all comprise a much greater number of parts and elements which are rather difficult of operation, as for example, 65 the ordinary shade supporting screws com-

mon in such holders, and which, when lost, render the shade holder practically useless. The close fit between the locking tongue 30 and the outwardly struck latching means 32 will provide a holder which cannot sag 70 or become warped in operation, and thereby prevents any accidental dropping of the shade.

I am aware that many changes may be made, and numerous details of construction 75 varied throughout a wide range without departing from the principles of this invention, and I, therefore, do not purpose limiting the patent granted hereon otherwise than as necessitated by the prior art. 80

I claim as my invention:

1. A shade holder including a circular plate, a downwardly extending flange integral with said plate, a diametrical cut in said plate, said cut being extended to one portion of the flange, the other portion of the flange diametrically opposite said cut comprising an integral spring hinge. 85

2. A shade holder including a circular plate, a downwardly extending flange integral with said plate, a diametrical cut in said plate, said cut being extended to one portion of the flange, with another portion of the flange diametrically opposite the cut 95 comprising an integral spring hinge, and a latching means on the flange opposite said integral spring hinge.

3. A shade holder including a circular plate, a downwardly extending flange integral with said plate, a diametrical cut in said plate, said cut being extended to one portion of the flange, another portion of the flange diametrically opposite the cut comprising an integral spring hinge, and a latching means on the flange opposite said integral spring hinge, said latching means comprising a plate fixed to the flange on one side of the cut, a tongue integral with said plate extending across the cut, and locking means on the other side of the cut adapted to co-operate with said tongue. 100

4. A shade holder including a circular plate, a downwardly extending flange integral with said plate, a diametrical cut in said plate, said cut being extended to one portion of the flange, another portion of the flange diametrically opposite the cut comprising an integral spring hinge, a latching means on the flange opposite said integral spring hinge, said latching means comprising a plate fixed to the flange on one side of the cut, a tongue integral with said plate extending across the cut, locking means integral with the flange on the other side of the cut adapted to co-operate with said flange, and means on the tongue adapted to automatically maintain the shade holder in locked relation. 110

5. A shade holder including a circular plate, a downwardly extending flange in- 120

tegral with said plate, a diametrical cut in said plate, said cut being extended to one portion of the flange, another portion of the flange diametrically opposite the cut comprising an integral spring hinge, and a latching means on the flange opposite said integral spring hinge, said latching means comprising a plate attached to the flange on one side of the cut, a tongue integral with said plate extending across the cut, locking means on the other side of the cut adapted to co-operate with said tongue, said tongue comprising a resilient element co-operating with said integral spring hinge, whereby the device will be automatically released from shade holding position upon an inward pressure on the end of said tongue.

6. A shade holder including a circular plate, a downwardly extending flange integral with said plate, a diametrical cut in said plate, said cut being extended to one portion of the flange, another portion of the flange diametrically opposite the cut comprising an integral spring hinge, a latching means on the flange opposite said integral spring hinge, and shade holding means integral with said downwardly extending flange comprising resilient lugs.

7. A shade holder including a circular plate, a downwardly extending flange in-

tegral with said plate, a diametrical cut in said plate, said cut being extended to one portion of the flange, another portion of the flange diametrically opposite the cut comprising an integral spring hinge, a latching means on the flange opposite said integral spring hinge, said latching means comprising a plate fixed to the flange on one side of the cut, a resilient tongue integral with said plate extending across the cut, locking means on the other side of the cut adapted to co-operate with said tongue, means on the tongue adapted to automatically maintain the shade holder in locked relation, and shade holding means integral with said downwardly extending flange comprising resilient strips.

8. A shade holder including a circular plate, a downwardly extending flange integral with said plate, a diametrical cut in said plate, said cut being extended to one portion of the flange, with another portion of the flange diametrically opposite the cut comprising an integral spring hinge, and a latching means on the flange opposite said integral spring hinge, said latching means including a guard adapted to prevent undue spreading of the shade holder.

In testimony whereof I affix my signature.
JAMES I. POLLAK.
